UNITED STATES PATENT OFFICE.

DAVID D. GORDON, OF CHICAGO, ILLINOIS, ASSIGNOR, BY MESNE ASSIGNMENTS, TO MCGILL MANUFACTURING COMPANY, OF VALPARAISO, INDIANA, A CORPORATION OF INDIANA.

SWITCH MOVEMENT.

Application filed January 29, 1918. Serial No. 214,288.

To all whom it may concern:

Be it known that I, DAVID D. GORDON, a citizen of the United States, residing at Chicago, in the county of Cook and State of Illinois, have invented a certain new and useful Improvement in Switch Movements, of which the following is a full, clear, concise, and exact description, reference being had to the accompanying drawings, forming 10 a part of this specification.

My invention relates to switch movements and has for its object the provision of a switch movement for electric circuits which in its preferred form is both of the quick 15 make and quick break variety.

The objects of the invention are to provide a novel switch movement which shall require but a very little movement of the control element in order to cause the operation thereof. Another object of the invention is to provide a novel switch movement 20 having very few operating parts and being readily and easily assembled. Another object is to provide a switch movement in 25 which the switch element is completely insulated from the remaining parts of the device. Another object of the invention is to provide a switch movement which shall be practically silent in its operation.

30 The movement itself of my invention so far as I am aware is entirely novel in its fundamental features. Its desirable characteristics and variety of applications will be readily apparent to those skilled in the 35 art from the detailed description of one form of my invention as applied to a lamp socket which I will now give in connection with the accompanying drawing illustrative thereof, in which

40 Fig. 1 is a longitudinal sectional view of one form of my switch mechanism as applied to a lamp socket;

Fig. 2 is a sectional view thereof on line 2—2 of Fig. 1;

45 Fig. 3 is a perspective view of the base plate;

Fig. 4 is a perspective view of two of the operating parts in their dis-assembled condition;

50 Fig. 5 is an end view of the right hand element in Fig. 4, and

Fig. 6 shows the parts of the switch movement in a reverse position to that shown in Fig. 1.

55 The socket illustrated in the drawings

consists of the porcelain parts 10 and 11 surrounded and enclosed by the customary shell and cover 13. An insulating connection 14 is provided within which the interior screw threaded contact 15 of the socket is placed, 60 there being also a center contact 16 insulated from the contact 15. The contact 15 terminates in a stationary switch contact 17. There is a co-operating switch contact 18 which is directly connected with the incoming leads. The center contact 16 is then also in the customary manner connected to the remaining of the incoming leads. In order thus to complete the circuit it is necessary to bridge the space between the stationary 70 switch contacts 17 and 18, and this is done through the agency of the U-shaped movable switch contact 19 which is designed to occupy two positions, the closed position, as indicated in Fig. 1, and open position as indicated in Fig. 6.

75 This metallic U-shaped movable switch contact is movable by snap action from its positions of circuit closure to circuit opening and from its position of circuit opening 80 to circuit closure. This snap action movement is brought about by means of the structure which will be presently described. This structure together with the element 19 is mounted upon the base plate 20. This base 85 plate 20 is held in position by the screw 21. This base plate 20 has the upwardly extending arm 22 carrying a seat 23 which projects beyond the confines of the socket. This seat carries the operating lever 24. This operating lever is loosely seated upon the seat 23 and is connected by means of a tension 90 rod 25 with the control element 26 of the movement. Whenever the lever 24 is tilted about its base into any angular position it 95 draws the tension rod 25 to the left. The lever 24 may be tilted into any desired angular position about its base and still effect a movement of the tension member 25 to the left (Fig. 1), as readily apparent. The base 100 plate 20 has two side walls 27 and 28 extending upwardly therefrom, which side walls then have inwardly converging extensions 29. The side walls 27 and 28 have outwardly extending lugs 30, which lugs carry fiber bearing sleeves 31. The movable switch arm 19 is rotatably seated upon the bearing sleeves 31 so that this switch arm 19 may be entirely insulated from the remaining parts 105 of the operating mechanism.

The control element 26 is shown more clearly in Fig. 4 and this control element co-operates with an operating element 32. The operating element is loosely placed in the movement so as to float or bodily shift from one operating position to another but confined in its position by having its lugs 33 seated within the slots 34 provided in the control element 26 and being united by means of the spring 35 with the movable switch element 19, this spring being preferably under extension or pull tension. The spring is secured to the operating element 32 as shown at 36 and the opposite extremity 10 of the spring is mounted in the insulating lug 37, this insulating lug 37 being mounted upon the outermost extremity of the movable switch element 19 and projecting therethrough as will be most clear from Figs. 1 and 2. Thus the movable switch element 19 is absolutely insulated from all of the remaining parts of the switch movement, including the elements 26, 32, 35, 20, 25 and 24. The left hand extremity (Fig. 1) of the operating element 32 is confined in its position by the plate extension 38 on the one side and by the extensions 29 on the other. The operating element 32 has fingers 39, which fingers co-operate with the right hand end 20 faces (Fig. 1) of the extensions 29 and 38.

By referring to Fig. 1, for instance, it is seen that this operating element 32 is held in the position it occupies by having its fingers 33 held in the slots 34 and by having the spring 35 draw its left hand extremity into engagement with the plate extension 38.

If now it is desired to reverse the position of the movable switch element 19, then 40 the lever 24 is tilted about its base in any suitable manner, or if desired, bodily drawn to the left (Fig. 1), whereupon the tension element 25 is moved to the left, this drawing the control element 26 to the left. The movement of the control element 26 to the left causes the operating element 32 to swing about the right hand edge of the extension 29 in a clockwise direction, this movement continuing until the left hand extremity of the spring 35 has passed beyond the center line 45 of the projections 30. During all this movement the spring 35 has been extended and immediately the left hand extremity of the spring has passed above the projection 30, 50 the movable switch element 19 swings by snap action into the position shown in Fig. 6, also drawing the left hand extremity of the operating element 32 toward the extension 29 by snap action. In this movement of the operating element 32, the lower fingers 39 have passed interiorly of the plate extension 38 and have not engaged the right hand face of this plate extension. The minute the pull or tension upon the lever 60 65 24 is reduced, however, so that the tension

element 25 and the control element 26 may again move to the right, the spring 35 draws these elements to the right, at the same time that it draws the operating element 32 to the right. As this operating element 32 is drawn to the right, the lower fingers 39 which are sliding along the upper face of the plate extension 38 finally pass beyond the right hand extremity of this plate extension and snap into position 70 in a manner similar to that in which the element 32 is shown engaging the extensions 29 in Fig. 1. The position now occupied by the parts is shown in Fig. 6. If then, the lever 24 is again actuated to draw 80 its tension member 25 to the left, the operating element 32 now swings contra-clockwise about the right hand edge of the extension 38 as a pivot carrying the left hand extremity of the spring below the finger 85 30, whereupon the movable switch element 29 snaps into the position shown in Fig. 1.

It will be noted that but one spring is utilized for the entire device and that this particular movement gives both a quick make 90 and quick break for the circuit under its control. It will also be noted that the spring 35 abuts the right hand extremities of the extensions 38 and 29, and the spring thus cushions the moving parts and makes the 95 device practically silent. It will also be seen that the movable switch element 19 is entirely insulated from the remaining parts of the mechanism so that the lever 24 may be of metal, if desired.

Many modifications may be made without departing from the spirit of the invention herein disclosed and many different applications may be made of it.

Having however thus described merely 105 one form which my invention may take, what I claim as new and desire to secure by Letters Patent is:

1. A switch movement having a switch element swingable between two alternative 110 positions, and means for moving said switch element from either of its positions to the other position by snap action, said means comprising an operating element and a spring connection extending from said operating element to said switch element so as to move said switch element from each position to the other by snap action, and a longitudinally reciprocatory control element, said control element being connected 115 with said operating element by means of fixed pivots.

2. A switch movement having a movable switch element and means to move said switch element from one to its alternative 125 position by snap action, said means including a floating bodily shiftable spring operating element connected to said switch element, by a spring connection only so as to move the switch from each position to the 130

other by snap action, and a reciprocatory control element operatively connected with said operating element.

3. The combination with a lamp socket comprising a shell, of a switch movement having a frame carrying a fixed seat protruding from the shell, a lever universally tiltably resting on the seat whereby the seat acts as a fulcrum for the lever, and means connecting the lever through the seat to the switch movement.

4. A switch movement having a movable switch element and means to move said switch element from one to its alternative position by snap action, said means including a control element movable alternately in opposite directions, a floating bodily shiftable operating element, and a spring interposed under extending or pull tension between said operating element and said switch element, said operating element being confined in its position by said control element and said spring.

5. A switch movement having a movable switch element and means to move said switch element from one to its alternative position by snap action, said means including a control element movable alternately in opposite directions, a floating bodily shiftable operating element, and a spring interposed under extending or pull tension between said operating element and said switch element, said operating element being confined in its position by said control element and said spring, said control element having means to move said operating element from one to an alternative position, thereby to bodily shift one extremity of said spring.

6. The combination with a lamp socket comprising a slotted shell, of a switch movement having a frame carrying a fixed seat protruding from the shell, a universally tiltably lever resting on the seat whereby the seat acts as a fulcrum for the lever, and a link of fixed length pivotally secured to the lever and to the switch movement for connecting the lever through the seat to the switch movement.

7. A switch movement having a movable switch element and means to move said switch element from one to its alternative position by snap action, said means including an operating element yieldingly connected to said switch element, a reciprocatory control element movably connected with said operating element, and a framework having two abutments pivotally co-operating with said operating element so as to permit alternate pivotal movements thereof to move the switch element from one to its alternate position.

8. A switch movement having a movable switch element and means to move said switch element from one to its alternative position by snap action, said means includ-

ing a floating bodily shiftable operating element yieldingly connected to said switch element, a reciprocatory control element movably connected with said operating element, and a framework having abutments co-operating with said operating element.

9. In a device of the character described, a shell, a switch mechanism within said shell, a bearing portion projecting from within said shell, a lever having an end portion engaging said bearing portion and tilttable thereon in any direction, and a pull connection extending from the lever through the bearing portion to said switch mechanism.

10. A switch movement having a movable switch element and means to move said element from one to its alternate position, said means including a frame having alternate pivotal points, a manually operable control element movable alternately in opposite directions, an operating element connected to the control element and operable to hook over the said pivotal points of the frame work in alternate positions, and a spring interposed between the operating and switch elements to effect operation of the switch element.

11. A switch movement having a movable switch element and means to move said element from one to its alternate position, said means including a frame having alternate pivotal points, a manually operable control element movable alternately in opposite directions, an operating element connected to the control element and operable to hook over the said pivotal points of the frame work in alternate positions, and a spring under extending or pull tension interposed between the operating and switch elements to effect said operation of the switch element.

12. A switch movement having a movable switch element and means to move said element from one to its alternate position, said means including a frame having alternate pivotal points, a manually operable control element lineally movable alternating in opposite directions, an operating element connected to the control element and operable to hook over the said pivotal points of the frame work in alternate positions, and a spring interposed between the operating and switch elements to effect said operation of the switch element.

13. A switch movement comprising a movable switch element movable from one to an alternate position, a manually operable reciprocable switch operating member, means connecting the said operating member and switch element so that for each complete reciprocation of the manual member said switch element is moved from one position to another by snap action, said means including a single spring for effecting such movement of the switch element and the restoring reciprocation of the manual member.

- 4 14. A switch movement comprising a movable switch element movable from one to an alternate position, a manually operable reciprocable switch operating member, means connecting the said operating member and switch element so that for each complete reciprocation of the manual member said switch element is moved from one position to another by snap action, said means including a single spring under extending or pull tension for effecting such movement of the switch element and the restoring reciprocation of the manual member.
- 5 15. A switch movement comprising a pivoted switch element movable from one to an alternate position at its free end, a lineally reciprocable manually operable member, an intermediate link pivotally connected at one end to one end of said member and having 10 a free end extending toward the other end of said member, and an operating spring for the switch element extending from the free end of the link past its pivotal point to the switch element.
- 10 16. The combination with a lamp socket comprising a shell, of a switch movement having a frame carrying a fixed seat protruding from the shell, a lever universally tiltably resting on the seat whereby the seat acts as a fulcrum for the lever, and means connecting the lever through the seat to the switch movement, said protruding part also 20 acting as guide to prevent rotary movement in the shell.
- 15 17. Switching mechanism comprising a switch movement having a frame, a flanged seat element on the frame, a tilttable lever element seating upon the flange, a connection between the lever and movement, and 30 a guiding cooperating boss and recess upon said elements.
- 20 18. Switching mechanism comprising a switch movement having a frame, a seat on the frame, a tilttable lever having a recessed 40 end resting upon the seat, a connection between the lever and movement, and a guiding boss upon the seat extending into the lever recess.
- 25 19. Switching mechanism comprising a switch movement having a frame, a seat on the frame, a lever having a base peripherally resting on the seat, a connection from the lever to the movement through the seat, and 50 guiding means whereby said lever may be universally tilted on its peripheral contact 55 with the seat at fixed points on the seat.
- 5 20. Switching mechanism comprising a switch movement, a seat, a lever having a peripheral base resting on the seat, a connection from the lever to the movement, and 60 guiding means whereby the lever may be tilted in various directions on its peripheral contact with the seat at fixed points on the seat.
- 10 21. A switch movement having a movable 65 switch element and means to move said element from one to its alternate position, said means including a frame having alternate abutments, a manually operable control element movable alternately in opposite directions, an operating element connected to the control element for co-operative engagement with said abutments of the frame work in alternate positions, and a spring interposed 70 between the operating and switch elements 75 to effect said operation of the switch element.
- 15 22. A switch movement having a movable switch element and means to move said element from one to its alternate position, said 80 means including a frame having alternate abutments, a manually operable control element movable alternately in opposite directions, an operating element connected to the control element for co-operative engagement with said abutments of the frame 85 work in alternate positions, and a spring under extending or pull tension interposed between the operating and switch elements 90 to effect said operation of the switch element.
- 20 23. A switch movement having a movable switch element and means to move said element from one to its alternate position, said 95 means including a frame having alternate abutments, a manually operable control element lineally movable alternately in opposite directions, an operating element connected to the control element for co-operative engagement with said abutments of the frame work in alternate positions, and a spring interposed 100 between the operating and switch elements to effect said operation of the switch element.

In witness whereof, I hereunto subscribe my name this 25th day of January, A. D., 1918.

DAVID D. GORDON.
